HAROLD E. STOUT, OF WEST READING, PENNSYLVANIA

MAILING TUBE

Application filed April 7, 1928. Serial No. 268,210.

This invention relates to mailing tubes.

An object of the invention is the provision of a mailing tube having a stiffened end portion.

5 Another object is the provision of a mailing tube having means for retaining papers within the tube.

Mailing tubes of the type now known to the art have a tendency to be weak at the ends 10 and in order to overcome this weakness various means have been used, for example, strips of paper or similar material have been pasted around the ends of the tube in order to prevent the ends from injury during use. Mailing tubes made in this manner are somewhat 15 more rugged than an ordinary mailing tube, but still have the disadvantage of not holding the papers enclosed therein against longitudinal displacement.

20 According to my invention, I stiffen the ends of a mailing tube and at the same time provide means for preventing papers within the tube from sliding out, by turning in the 25 end portions of the tube. The turning in of the end portions of the tube provides a stiffening support for the ends of the tube and at the same time turns the raw edge in leaving a smooth rounded surface on the outside, which not only adds to the appearance 30 of the tube, but also adds to its utility. The inwardly turned portion or ridge acts as a stop for preventing papers on the inside of the tube from sliding out and also as a guiding means for facilitating loading of the tube.

35 When papers are being thrust into the tube, the rounded end portion acts as a guide and at the same time reduces the friction between the rolled papers and the tube. This feature is most apparent when a heavy roll of papers 40 are to be placed in a relatively small tube. A roll of papers positioned in the tube have a tendency to uncurl and thus assume a larger diameter, and in doing so make themselves large enough so that it is impossible for them 45 to slip out past the ridge. This feature of the invention eliminates the need of end closures for mailing tubes and thus greatly adds to their effectiveness.

I find that the ends of a tube can readily 50 be curled or turned inwardly by a spinning

process, this being carried out by means of a die having a rounded groove into which the end of a tube may be pressed and the tube rotated. I find that if a plurality of holes are placed in the bottom of the groove in the 55 die that the curling operation is facilitated. The holes aid in directing the end walls of the tube inwardly so that less force need be used in thrusting the end of the tube against the die in the spinning operation. This reduction in pressure reduces the wear on the end of the tube and prevents burning there- 60 of due to friction.

In carrying out the invention, the ends of a tube may be turned in to a greater or lesser 65 extent as desired depending on the material used and the use to which the tube is to be put.

The above mentioned and other objects and 70 advantages and the manner of attaining them will be made clear in the following description taken in connection with the accompanying drawings.

In the drawing, Fig. 1 shows a vertical 75 section of a tube constructed in accordance with my invention.

Fig. 2 is an end view of the tube shown in Fig. 1.

Fig. 3 illustrates in vertical section, the end 80 of a tube positioned in the die during the curling process.

Referring more particularly to the drawings, reference numeral 1 indicates a mailing tube having inwardly turned end portions 2. As illustrated in Fig. 3, the end of the tube 85 1 is thrust into an aperture 3 in a die 4, said aperture having a rounded outer edge 5 and terminating at its inner end in an annular shaping groove 6, the groove 6 being provided with a plurality of spaced holes 7 in 90 the bottom thereof.

The curling of the end of the tube is accomplished by thrusting the tube against the die as indicated by the arrow in Fig. 3, and at the same time rotating the tube with respect to the die. As the tube is forced against the die and rotated, the end of the tube is caused by the groove 6 to turn inwardly in reentrant fashion. This inward turning is 95 aided by the holes 7 which, due to the pres- 100

sure forcing the tube against the die act upon individual portions of the end of the tube wall, which are forced into the holes, thus turning these portions inwardly progressively. The groove in the die may advantageously have four holes but a greater or lesser number may be used as desired. Likewise, the die can be used without the holes 7, but greater pressure between the tube and the die is necessary and this greater pressure may cause burning of the end of the tube during the curling operation.

In order to insure that the tube will not be injured by contact with the edges of the holes 7, these edges are made rounded as indicated at 8.

I have shown a tube during the process of having one end turned in but it will be understood that if desired to speed up the curling operation both ends of the tube might be operated on at once. Either the tube or the die may be rotated, it makes no difference as long as there is relative rotation between the two.

While I have, for the purpose of illustration, disclosed a particular embodiment of my invention, it will be understood that the various embodiments and modifications such as would occur to one skilled in the art, may be made without a departure from the spirit of the invention as set forth in the appended claim.

What I claim is:

A mailing tube having the ends thereof turned over so that the cross-section of the wall at the end of the tube is in the form of a semi-circle to form a stiffening rib and to serve as a gripping edge for the tube contents.

In testimony whereof, I have signed my name to this specification this 24th day of March, 1928.

HAROLD E. STOUT.
